UNITED STATES PATENT OFFICE.

WILLIAM ACHESON SMITH, OF NIAGARA FALLS, NEW YORK, ASSIGNOR TO INTERNATIONAL ACHESON GRAPHITE COMPANY, OF NIAGARA FALLS, NEW YORK.

METHOD OF HEATING CARBON.

1,004,923.

Specification of Letters Patent.

Patented Oct. 3, 1911.

Application filed December 20, 1910. Serial No. 598,300.

To all whom it may concern:

Be it known that I, WILLIAM ACHESON SMITH, a citizen of the United States, residing at Niagara Falls, in the county of 5 Niagara and State of New York, have invented certain new and useful Improvements in Methods of Heating Carbon, of which the following is a specification.

This invention relates to the electrical 10 heating of commercial forms of carbon for the purpose of expelling volatile matters therefrom, or under appropriate conditions for purifying the carbon, baking carbonaceous compositions, polymerizing carbon or 15 converting it into graphite. Heretofore such operations in the electric furnace have usually been intermittent in character, and attempts to render them continuous or substantially continuous have, so far as I am 20 informed, proven impractical.

Such commercial forms of carbon as petroleum coke, gas coke, anthracite coal and the like undergo when heated a series of successive modifications dependent not only 25 upon the temperature to which they are heated, but upon the duration of the heat treatment. They do not however undergo any marked change in bulk such as is characteristic of most metallurgical or reducing 30 operations. For example, moderate heating, or heating for a brief period to a high temperature, results in the expulsion of volatile hydrocarbons; by longer heating at sufficient temperatures such impurities as silica, alumina, lime, oxids of iron, etc., are driven off, and the carbon undergoes a progressive increase in density and 35 electrical conductivity and becomes polymerized, and may be converted ultimately 40 into graphite.

For many industrial uses, as for example electrode compositions, battery fillers, etc., a close adjustment of time and temperature is required to convert a given raw 45 material into a product of the desired character; and for the performance of operations of this kind the intermittently-operated furnace is always employed in practice. In all cases where it has been sought 50 to render the operation of electrically heating carbon continuous, so far as I am aware, the electric current has been caused to traverse the body of the carbon or carbonaceous material constituting the charge, 55 in a direction transverse to the direction of

movement of the charge, that is to say, either at right angles or in other angular relation thereto, the result in all cases being that the charge fails to receive the prolonged treatment under substantially uniform 60 temperature conditions which is essential to securing the best results, whether the object be to shrink, purify, polymerize or graphitize the charge.

A further defect of prior operations in 65 which the heating current traversed the charge under treatment, is that it has heretofore proven impracticable to secure that distribution or limitation of the path of the current which would be most advantageous for the purposes in view. The conductivity of carbon increases with the temperature, and the current tends therefore to follow indirect and irregular paths which include the more highly heated portions 70 of the charge. For the same reason there is a strong tendency for the current to follow restricted paths between the electrodes with the result that whereas a portion 75 of the carbon may be heated to an uncontrollably high temperature, other portions thereof traverse the furnace without adequate or proper heating. The resulting lack of uniformity in the product renders it quite unsuitable for any technical use. 80

According to the present invention the electric current for heating is passed either through the body of the charge as a resistor, or wholly or in part through a resistor independent of the charge, between 90 terminals which are comparatively widely spaced; and the charge is progressively advanced either continuously or intermittently, in a direction which is substantially 95 parallel to the lines of flow of the electric current. In this way the charge may be subjected for such period as may be desired, depending upon the rate of advance of the charge, to substantially uniform temperature conditions; and it is found that by 100 controlling the factors of time and temperature the desired product may be obtained with certainty and uniformity. This principle may be carried into effect in various ways, it being essential in all cases that 105 such localization of the current as would result in uneven or irregular heating should be avoided.

Certain forms of apparatus which have 110 been found satisfactory for carrying out

the invention are shown in the accompanying drawing, wherein:

Figure 1 is a central vertical section of one form of electric furnace adapted for the practice of the invention; and Fig. 2 is a similar view of a slightly modified construction.

In said drawing, 1 represents the wall of a furnace of the vertical shaft type, having a bottom discharge mechanism comprising a horizontal disk or slightly coned hearth 2, mounted for slow rotation by means of a worm gear 3, and adjustable relatively to the base of the furnace so that the material is discharged over the periphery of the hearth only while the same is being rotated.

4 indicates a space in the furnace walls adjacent the heating zone, said space communicating by inclined apertures 4^a both with the heating chamber and the external air, in order that the furnace gases may readily escape from the heating zone, and that a mantle of such gases may be burned within the furnace wall to economize heat.

5 indicates cooling means, represented as a system of water pipes, between the heating zone and the discharge hopper. The cooling means may be disposed in the path 30 of the charge as in Fig. 1 or in the furnace walls as in Fig. 2, the former construction being regarded as preferable.

In the construction illustrated in Fig. 1 the furnace charge is intended to serve as the heating resistor, interposed between vertically-aligned, axially-arranged upper and lower terminals or electrodes 6 and 7, which are of carbon or graphite. The working end of the upper electrode 6 is embedded in the charge 8, as is also the lower electrode 7. The lower electrode is shown as supported axially of the furnace by a hollow metal bar or casing 9 carried by the furnace walls; water may be circulated through this electrode support by means of appropriate connections 10. 11, 12 represent the electrical connections to the upper and lower electrodes, respectively. Instead of the hollow electrode support 9 shown in Fig. 1, I may use a graphite bar 13, Fig. 2, into which the lower graphite electrode 7 is screwed or to which it is otherwise secured.

In Fig. 2 I have illustrated a resistor 14 in the form of a carbon or graphite rod extending between the terminals 6 and 7, this construction being particularly useful when the charge, in its unheated state, is a comparatively poor conductor of electricity.

In either construction the lower electrode 6 is so supported that the downward movement of the charge is not substantially impeded, such movement being controlled by the hearth 2. Obviously, the single carbon pencil constituting the upper electrode may be replaced by a group of such pencils, but

in such case it is advisable to provide suitable means for securing a substantially even distribution of the heating effects from the several electrodes. This may be accomplished by known methods, as for example by making the several pencils the terminals of a polyphase heating circuit, by the provision of suitable automatic regulators for the individual pencils, etc.

In operation, the furnace is filled with carbon or carbonaceous material in a suitably subdivided state and the electric circuit is closed, an independent resistor or starting core being used or not as the conditions may require. The portion of the charge between the electrodes is heated to a high and substantially uniform temperature, and as the heating process is advanced, either continuously or by stages. The movement of the charge is in a direction substantially parallel to the lines of current flow, and the charge is subjected to substantially equable temperature conditions for a period which is dependent upon its rate of advance, the actual temperature being controlled by the quantity of current passing. By proceeding in this way, all factors being under control of the operator, it has been found possible so to regulate the operation that a substantially uniform product of the desired character is obtained.

I claim:

1. The method of heating carbon and preparing therefrom a commercially uniform product, which consists in passing an electric current between terminals embedded in a body of carbon or carbonaceous material supported by fixed refractory walls, and advancing said body in a direction substantially parallel to the lines of current flow.

2. The method of heating carbon and preparing therefrom a commercially uniform product, which consists in passing an electric current between terminals axially embedded in a body of carbon or carbonaceous material supported by fixed refractory walls, and advancing said body in a direction substantially parallel to the lines of current flow.

3. The method of heating carbon and preparing therefrom a commercially uniform product, which consists in passing an electric current through a body of carbon or carbonaceous material supported by fixed refractory walls and serving as a heating resistor between terminals within the interior of said body, and advancing said body in the direction of its axis.

4. The method of heating carbon and preparing therefrom a commercially uniform product, which consists in passing an electric current through a body of carbon or carbonaceous material supported by fixed refractory walls and serving as a heating resistor between terminals substantially

axially disposed within the interior of said body, and advancing said body in the direction of its axis.

5. The method of expelling volatile constituents from commercial forms of carbon and preparing therefrom a commercially uniform product, which consists in passing an electric current between terminals embedded in a body of carbon or carbonaceous 10 material supported by fixed refractory walls, and advancing said body in a direction substantially parallel to the lines of current flow.

6. The method of shrinking petroleum coke, which consists in passing an electric current through a body of petroleum coke between terminals embedded therein, and advancing said body in a direction substantially parallel to the lines of current flow.

7. The method of polymerizing carbon 20 and preparing therefrom a commercially uniform product, which consists in passing an electric current between terminals embedded in a body of carbon or carbonaceous material supported by fixed refractory walls, 25 and advancing said body in a direction substantially parallel to the lines of current flow, the temperature and duration of treatment being sufficient to impart increased density and electrical conductivity to the 30 carbon.

*In testimony whereof, I affix my signature in presence of two witnesses.
